(57) **CLAIM**

The ornamental design for a handle for doors of protection barriers for industrial machine as shown and described.

DESCRIPTION

1. Handle for doors of protection barriers for industrial machine

2. Handle for doors of protection barriers for industrial machine

1.1 : Perspective

1.2 : Front

1.3 : Back

1.4 : Right

1.5 : Left

1.6 : Top

1.7 : Bottom

2.1 : Perspective

2.2 : Front

2.3 : Back

2.4 : Right

2.5 : Left

2.6 : Top

2.7 : Bottom

The broken lines in the figures show portions of the handle for doors of protection barriers for industrial machine which form no part of the claimed design.
